ANTI-SKID FLOOR PLATE

Otto A. Klein, Grosse Ile, Mich., assignor to National Steel Corporation, a corporation of Delaware

Filed Sept. 11, 1961, Ser. No. 66,671

Term of patent 14 years

(Cl. D13—1)

FIG. 1

FIG. 2

FIGURE 1 is a plan view of an anti-skid floor plate showing my new design; and

FIGURE 2 is an enlarged fragmentary perspective view of a single projection on the floor plate of FIGURE 1.

I claim:

The ornamental design for an anti-skid floor plate, as shown.
